A. HALLOWELL.
METHOD OF STRENGTHENING BOBBINS OR SPOOLS.

No. 100,754.

Patented Mar. 15, 1870.

United States Patent Office.

ALBERT HALLOWELL, OF LOWELL, MASSACHUSETTS, ASSIGNOR TO HIMSELF, ABEL T. ATHERTON, AND HORACE T. DURGIN, OF SAME PLACE.

Letters Patent No. 100,754, dated March 15, 1870.

IMPROVEMENT IN METHOD OF STRENGTHENING BOBBINS OR SPOOLS.

The Schedule referred to in these Letters Patent and making part of the same.

To all whom it may concern:

Be it known that I, ALBERT HALLOWELL, of Lowell, in the county of Middlesex, and State of Massachusetts, have invented certain new and useful Improvements in Bobbins or Spools, of which the following is a full, clear, and exact description, reference being had to the accompanying drawings making part of this specification, in which—

Figures 1, 2, and 3 represent each a central sectional elevation.

Figures 4 and 5 represent each an end view.

This invention has for its object to cover or partly cover, and to strengthen and protect one or both of the heads or ends of the bobbin or spool, thereby preventing splits, cracks, or roughness, which materially injure or spoil the bobbin before it is half worn.

This invention consists in the method, substantially as described, of strengthening, protecting, and preserving one or both ends or heads of the bobbin or spool, by means of a metal hoop, band, or ring, *a*, or that and a protecting plate, *c*, combined, and either of these cast onto the head or end, and into an annular groove previously formed in the substance of the bobbin or spool for the reception of the metal, which, while in a melted state, fills the groove and forms the strengthening ring, which shrinks in cooling, binds the wood and prevents it splitting and protects it.

To apply this ring or hoop to the head or end of the bobbin, after turning the groove, the head or end which is to be hooped, or hooped and plated is placed in a common metal mold, hinged or pinned together in the usual way.

Some portion of the mold *A* must fit some part of the bobbin, say the barrel *B*, leaving a sufficient open space between the interior of the mold and the exterior of the head or end to be filled with melted metal and form the ring, or that and the plate combined.

The metal is poured into the mold through a suitable gate, filling the open space in the mold above referred to, and forming the desired ring or ring and plate combined, all as clearly shown in the drawings. The mold is then opened, the bobbin removed, and any surplus metal removed in the usual way of turning or otherwise finishing the ring, or that and the plate, to the desired degree of thickness, form, or smoothness.

The metal used to cast the ring or the ring and plate must be that which is fusible at a low degree of heat, so as not to burn the wood, and I generally use a composition of tin, zinc, and bismuth, or that which is known by persons skilled in the art of casting in molds as white metal, which is equally as good. In fact, any metal which melts at a low temperature will answer the purpose described; but iron, copper, brass, or such metals as require a high degree of heat to melt them, will not answer the purpose.

External grooves *g* may be cast in the metal hoop or plating, to serve the purpose of holding the bobbin onto the shuttle-spindle or for any purpose desired.

In all cases I cast the metal into an annular groove, as shown, so as to hold the ring or the ring and plate firmly on the head or end of the bobbin or spool.

I claim the method, substantially as described, of strengthening, protecting, and preserving one or both heads or ends of a bobbin or spool, by means of a metal band or hoop, or a band or hoop and a plate combined, by casting the metal into an annular groove around the head or end of the bobbin, or in said groove and over and upon the end portion, substantially in the manner and for the purpose set forth.

ALBERT HALLOWELL.
